FIG. 3.

UNITED STATES PATENT OFFICE.

CHARLES J. DORSEY, OF BALTIMORE, MARYLAND.

FIGURE TOY.

SPECIFICATION forming part of Letters Patent No. 729,555, dated June 2, 1903.

Application filed September 20, 1902. Serial No. 124,175. (No model.)

To all whom it may concern:

Be it known that I, CHARLES J. DORSEY, a resident of Baltimore, in the State of Maryland, have invented certain new and useful Improvements in Figure Toys; and I do hereby declare the following to be a full, clear, and exact description of the invention, such as will enable others skilled in the art to which it pertains to make and use the same.

10 The invention relates to figure toys, and has for its object to produce a movement of figures by simple and certainly acting mechanism and in an amusing manner.

15 The invention consists in the construction hereinafter described and pointed out.

In the accompanying drawings, Figure 1 is a perspective of the toy. Fig. 2 is a plan. Fig. 3 is a partial elevation. Fig. 4 is a partial section of a slide. Fig. 5 is a partial section of a detail. Fig. 6 is a perspective of balloon-releasing devices.

20 Numeral 1 represents a shallow open-bottomed box supported, preferably, on feet 2 and having in its top a curved slot 3, which by preference is circular. Fixed to the top of the box on its under surface is a spring-holding block or stud 4, a spring being denoted by 5.

25 6 indicates a slide curved to correspond to the slot. To the bottom of the slide are fixed pins or rollers 7 suitable to travel in the slot and to guide the slide when moved by the spring.

30 8 denotes a slide to hold the catch against the normal tendency of the spring when under tension to move it.

35 9 indicates a figure, which may be that of a horned or other animal, which is pivotally supported on a short fixed post 10, the pivot and post being by preference concealed, as indicated.

40 11 denotes another figure, which may be that of a man supported on a pin 12, rising from the end of the spring, as shown, said pin constituting a connection between the slide and the spring and also connecting the figure to the same.

45 13 indicates a balloon or the like, which is overbalanced by a weight 14, movable up and down in the hollow post 15, fixed to the top of the box. The weight is connected to the

figure by a cord or the like passing over pulleys 15. For convenience for packing or transportation the post is made in telescoping sections.

55 At the bottom of the balloon is a hook or catch 16, adapted when the balloon is drawn down to enter a slot in a short post 17 and to be engaged and held in such situation by a two-armed button 18, pivotally supported in a weight 19. When so engaged, the button holds the balloon down and holds the weight up. To the weight 19 is connected a wire lever 20. The weight and its connected wire are pivotally supported on a pin 21, extending between the small posts 22.

23 denotes a hole in the box-top, and 24 is an extension of the same, within which is the pivotal connection of the wire 20 and the pin 21. A spring 25 may be used to steady the movements of the weight and wire.

70 To operate the toy, the catch or detent 8 is released, whereupon the spring moves the slide rapidly around the curve and against the free arm of the button 18 and also against an elastic button 29 with the effect to turn the button and release both the button and weight. Simultaneously the figure 11, by means of a handle or other suitable catch 26, engages the catch 16 of the balloon, so as to ascend with it, and the projection 27 of the weighted lever engages a part 28 on the pivoted figure to cause it to turn on its pivot, which in the case illustrated gives the appearance of the animal rearing on its hind legs to follow the ascending figure.

75 Having described my invention, what I claim as new, and desire to secure by Letters Patent, is—

1. In a toy, the combination of the slotted base, a slide carrying a plurality of figures including a figure pivoted to the slide, and including a second figure detachably connected to the slide, and means to move the slide and devices to detach the latter figure from the slide and move it away from the pivoted figure and devices to turn the latter on its pivot.

2. In a toy, the combination of a base, a slide carrying a plurality of figures including a figure pivoted to the slide, and including a second figure detachably connected to the

slide, and means to move the slide and detach the latter figure, and mechanism to elevate the detached figure.

3. In a toy, the combination of a base, a slide carrying a plurality of figures including a figure pivoted to the slide, and including a second figure detachably connected to the slide, and means to move the slide and detach the latter figure, and mechanism to move the pivoted figure.

4. In combination, a slide, a base provided with a slide-guide, a figure pivoted to the

slide, and mechanism to turn the figure on its pivot, said mechanism comprising a lever normally inoperative, a weight to operate the lever, and a detent for the weight, said detent being in the path of the slide. 15

In testimony whereof I have signed this specification in the presence of two subscribing witnesses.

CHARLES J. DORSEY.
